SELF-FEATHERING FAN

Samuel D. Bell, Keego Harbor, Mich.

Application July 17, 1950, Serial No. 174,177

3 Claims. (Cl. 170—160.11)

1

This invention relates generally to cooling fans of the type employed in connection with vehicle propelling engines for cooling purposes and refers more particularly to improvements in fans having blades or vanes which decrease in pitch as the engine speed increases.

It is an object of this invention to provide a cooling fan having a rotatable hub and having a plurality of circumferentially spaced radially outwardly extending vanes or blades supported on the hub by mountings which, although exceptionally simple, nevertheless, assure reducing the pitch of the various blades when the engine speed exceeds a rate where cooling by the fan is no longer required or in any case is substantially reduced. Thus the power required to drive the fan at elevated engine speeds is materially reduced and the operating efficiency of the engine is greatly increased.

The foregoing as well as other objects will be made more apparent as this description proceeds, especially when considered in connection with the accompanying drawing, wherein:

Figure 1 is an elevational view of a cooling fan embodying the features of this invention;

Figure 2 is an enlarged elevational view of a part of the fan shown in Figure 1;

Figure 3 is a view similar to Figure 2 showing the parts in a different position;

Figure 4 is a sectional view taken on the line 4—4 of Figure 2; and

Figure 5 is a sectional view taken on the line 5—5 of Figure 2.

The cooling fan selected herein for the purpose of illustration comprises a hub 10 and a plurality of blades or vanes 11. The blades 11 are spaced from each other circumferentially of the hub 10 and extend generally radially outwardly from the hub 10. The fan is especially designed for use in connection with an automobile vehicle propelling engine and the hub 10 is designed for attachment to a suitable shaft driven by the engine in the usual manner.

The blades 11 are formed separately from the hub 10 and are mounted on the hub in a manner such that the pitch of the blades varies in accordance with the magnitude of the forces acting on the blades as a result of rotation of the hub 10. The principal forces which act on the blades in operation are centrifugal force and the resistance of the atmosphere to the passage of the blades 11 through it. Generally speaking these forces increase as the speed of the engine or the speed of the hub 10 increases, and act to reduce the pitch of the blades 11. The general arrange-

2

ment is such that at low speeds when the circulation of air due to the movement of the vehicle is at a minimum, the pitch of the blades 11 is at a maximum so that the full capacity of the fan is available to assist in cooling the engine. On the other hand, as the speed of the engine or hub 10 increases, the pitch of the blades 11 becomes less; and as a result, the fan consumes less power and creates less noise at higher speeds.

With the above in view, reference is made more in detail to the specific mounting of the blades 11 on the hub 10. All of the blades 11 are supported on the hub 10 by identical mountings, and accordingly, a description of one mounting will suffice for all. As shown in the drawing, a bushing 12 is welded, brazed or otherwise secured to one side of the hub 10 with its axis extending radially in relation to the hub axis, and a second bushing 13 is similarly secured to the blade 11 with its axis aligned with the axis of the bushing 12. The bushing 13 is fixed to one side of the blade 11 at the bottom of the latter, and is positioned substantially midway between the opposite side edges of the blade 11.

The blade 11 is held in assembled relation with the hub 10 by a stud 14 which extends freely through the bushings and has a head 15 at the outer end adapted to seat on the adjacent end of the bushing 13. The inner end of the stud 14 extends for some distance below the inner end of the bushing 12 and a collar 16 is secured to the inner end of the stud by a suitable set screw 17. A suitable coil spring 18 surrounds the inner end of the stud 14 between the collar 16 and the inner end of the bushing 12. The coil spring 18 is normally under compression and functions to yieldably hold the adjacent ends of the bushings 12 and 13 in frictional engagement.

It will be noted particularly from Figures 2 and 3 of the drawing that the outer end of the bushing 12 is fashioned with a generally V-shaped recess 19, and the lower end of the bushing 13 is formed with a correspondingly shaped projection 20. The V-shaped projection 20 seats in the V-shaped recess 19 and cooperates with the latter in positioning the blade 11 at its maximum pitch angle with reference to the plane of rotation of the hub 10.

It follows from the above that all of the blades 11 are normally urged by their respective springs 18 to positions wherein they extend at the maximum pitch angle with respect to the plane of rotation of the hub. The blades 11 remain in

the above position until the forces acting on the blades as a result of rotation of the hub 10 overcomes the compression load on the springs 18. When this occurs the blades 11 rotate in the direction of the arrow A (Figures 2 and 3) about the studs 14 to reduce the pitch of the blades. As the blades 11 rotate about the respective axes of the studs 14, the bushings 13 secured to the blades rotate relative to the bushings 12 secured to the hub 10, and as a consequence, the sides 21 of the V-shaped projections ride outwardly on the adjacent sides 22 of the V-shaped recesses 19. If desired these sides may be curved slightly to provide a camming effect and facilitate rocking of the blades. In any case the blades 11 are displaced outwardly along the respective studs 16 as they rotate about the latter and the springs 18 are further compressed. Thus the springs 18 in conjunction with the angle of inclination of the V-shaped sides 21 and 22 determine the speed of the engine or hub 10 at which the pitch of the blades 11 is reduced, and any desired operating characteristic may be provided by changing the angle of inclination of the sides 21 and 22, and/or varying the compressive load on the springs; or by employing springs of different strength. The V-shaped projections and recesses also coact to guide movement of the blades 11 relative to the hub and assure quiet operation of the fan.

What I claim as my invention is:

1. In a cooling fan, a rotatable hub, a vane extending outwardly from the hub and rotatable as a unit with the hub, a bushing secured to the hub with its axis extending generally radially with respect to the hub axis, a second bushing secured to the vane in alignment with the first bushing, a pivot pin extending through said

bushings and having stops at opposite ends, the adjacent ends of the bushings having engaging surfaces inclined relative to the axis of the pivot pin in directions to move the vane outwardly 5 along said pin in response to the forces acting on the vane as a result of rotation of the hub, and a spring surrounding the pin and held under compression between the stop at the inner end of the pin and the adjacent end of said first bushing.

2. The cooling fan set forth in claim 1 in which one bushing has a generally V-shaped projection on the end adjacent the other bushing and the latter has a correspondingly shaped recess for 15 receiving said projection.

3. The cooling fan set forth in claim 2 in which the projection and recess cooperate with one another and with said spring to yieldably hold the vane in a position wherein it extends at the 20 maximum pitch angle relative to the hub.
